UNITED STATES PATENT OFFICE.

FRANK J. QUIST AND ANDERS E. ANDERSON, OF WORCESTER, MASSACHUSETTS, ASSIGNEES TO DOMESTIC VACUUM CLEANER COMPANY, OF WORCESTER, MASSACHUSETTS, A CORPORATION OF MASSACHUSETTS.

CARPET-CLEANER.

1,258,811.

Specification of Letters Patent. Patented Mar. 12, 1918.

Application filed March 2, 1916. Serial No. 81,624.

To all whom it may concern:

Be it known that we, FRANK J. QUIST and ANDERS E. ANDERSON, citizens of the United States, both residing at Worcester, in the county of Worcester and State of Massachusetts, have invented a new and useful Carpet-Cleaner, of which the following is a specification.

This invention relates to a carpet cleaner and is particularly adapted for that type of combination cleaners in which an electric motor is used to produce suction and a brush is employed operated by rollers traveling on the floor, but some of the features of the invention are applicable to the pneumatic type of cleaners in which the suction is produced by other means and others to brush sweepers.

The principal objects of the invention are to provide a carpet cleaner of the brush and suction combination type in which the range of operation of the suction shall extend beyond the ends of the brush and the mechanism for operating the brush shall not extend beyond the ends of the suction nozzle so that this operating mechanism will not limit the range of effectiveness of the device, and will permit it to work up to the edges of a room; to provide means whereby the brush bearings are prevented from being clogged with hair or threads; to provide an improved form of casing which will house the brush and also most of the operating means therefor and which can be made of sheet steel, so that it will have a maximum of strength with a minimum of weight; to provide a brush operating mechanism of an improved type so that the brush and operating wheels can be adjusted together or independently; to provide improved means for attaching the brush to its operating mechanism so that it can be readily detached and replaced; to provide improved means for preventing the drawing of a carpet or the like up into the nozzle; and to provide an improved form of handle adjusting device.

Reference is to be had to the accompanying drawings, in which—

Figure 1 is a side elevation of a combina-

tion electric and brush sweeper constructed in accordance with this invention;

Fig. 2 is a plan of the same on enlarged scale;

Fig. 3 is a front elevation thereof; 55

Fig. 4 is a bottom plan;

Fig. 5 is a detail sectional view on enlarged scale on the line 5—5 of Fig. 4;

Fig. 6 is an end view further enlarged;

Fig. 7 is a front view of a detail of the 60 brush supporting mechanism;

Fig. 8 is a front view of an adjusting device for the operating wheels;

Fig. 9 is a plan of the brush and brush-operating mechanism with the casing 65 broken away;

Fig. 9^a is a sectional view on the line 9^a—9^a of Fig. 9.

Fig. 10 is an end view of the brush showing the means for attaching it to the operating stud which is shown in section; 70

Fig. 11 is a side view of the handle holding and adjusting device, and

Fig. 12 is a view similar to a portion of Fig. 6 showing a modification. 75

The invention is illustrated in a form involving a main casing 10, motor casing 11, and fan casing 12 secured rigidly together. The fan is operated by the motor for drawing the air from the casing 10 and 80 delivering it to a dust-bag 13 through a connection 16. The motor is supported preferably by a single roller 14 at the rear while the casing 10 may be supported by a pair of rollers 15 and is usually adjusted so 85 that these constitute the support at this end of the structure.

The casing 10 is provided with a laterally enlarged main section which preferably has a comparatively wide slot 17 in its bottom 90 wall. The main casing is provided with two flat ends 18 at the ends of this slot and beyond each of these is a projection 19 integral with the casing and provided with a passage or extension 20 of the slot. This 95 extension is shown as narrower than the slot and preferably is narrower because no brush extends into it.

The projection 19 is preferably of a low flat character constituting a shelf for sup- 100

porting certain operating parts as will appear. This shelf is shown as flat on the bottom and inclined on the top and as carrying a bracket 21 having a post 22 extending upwardly therefrom near its forward end. These parts of course are duplicated at the other end of the casing. This post is provided with a vertical slot 23 and a sheet metal bearing member 24 is adjustably secured to it by screws 25. This bearing member is shown of a U-shaped form so as to afford two bearings for a brush operating shaft 26. On this shaft is a wheel 27 between the two legs of the U-shaped bearing plate. One end of the bearing plate projects beyond the wheel and is provided with a pivot stud 28 to which is pivoted a frame 29 which extends rearwardly from the pivot and across the casing at the rear. This frame is provided with a sheet metal slide 30 thereon to which is secured a stud 31 on which one of the operating rollers 15 is rotatably mounted. These operating wheels are provided with soft rubber tires which engage the carpet and also the wheels 27 to operate them. This frame 29 is provided with a stud or pin 32 adapted to enter any one of a series of holes 33 in an adjusting plate 34 fixed to the fan casing 12. The back plate of this frame is of spring metal so that it can be moved forward and back enough to engage and disengage the pin 32 for adjusting purposes.

The frame 29 is also provided with a longitudinal spring 35 which bears on projections 36 on the rear ends of the slides 30 to force the rollers 15 into contact with the wheels 27 with a spring pressure.

From this construction it will be seen that the studs 31 or rather the rollers 15 can be raised or lowered about the pivots 28 and also that the brush operating shafts 26 can be raised or lowered by a true vertical motion by raising the bearing plates 24 along the slots 23 at the two ends of the casing.

The casing 10 is formed of sheet steel stamped up in dies and welded and is formed so as to have a graceful curved shape throughout, except that its ends 18 make an angle with the projection 19 and the top of the casing. At this point a space is provided for the reception of the parts for operating the brush as has been described, these being supported on the projection 19. In order to complete the casing and give it a satisfactory form, and especially to hide the operating parts for the brush and prevent the settling of dust and dirt in them, a pair of end caps 37 are provided, each one also of sheet steel and secured to the end wall 18 and to the end of the projection 19. These caps are shaped in dies to form a graceful continuation of the outline of the main casing, and to cover

also the ends of the projections 19. They are removably located in position so that it is an easy matter to get at the screws 25 for adjustment. Yet they permit the location of the operating parts outside the casing and the extension of the dust slot outwardly at 20 to permit of using the suction part of the cleaner clear up to the surface against which the end of the casing comes. The movable operating parts except the shafts do not have to pass through the walls of the casing in order to secure these results. It will be understood that the ends 18 are provided with vertical slots 38 up and down which the shafts 26 are adjusted. By making the casing 10 and caps 37 of sheet steel they can be made very thin and light without sacrificing strength.

The manner of mounting and dismounting the brush is also a feature of this invention. Each of the brush operating shafts 26 is made with a non-circular end 39 and the brush 40 is provided with a shaft 41 having two metallic ferrules 42, one of which has a slot centrally located of the same shape as the end 39 so that when placed in position the brush is positively rotated from this shaft. The other one of these metallic ferrules is provided with a slot 43 extending from the edge to the center for the reception of the corresponding end 39 on that shaft. Also secured to this ferrule 42 is a sheet metal bracket 45 having a bifurcated end 46 provided with a substantially circular socket adapted to receive the circular portion of the brush operating shaft 26 at that end and guide it into position so that the brush can be readily reapplied when detached and its socket forced into proper position for receiving the operative end of the shaft or stud 26.

One of the important features is the mounting of the bearings for the brush outside the casing so that they will not get clogged up by hair and threads passing by them. To make this practical each of the brush studs or shafts 26 is provided with a felt washer 47 and a flat metal plate 48 arranged loosely just outside the slot 38. The plates are pressed inwardly by spring projections 49 and the suction also tends to hold the washers against the ends of the casing so that the entrance of air is prevented and yet the brush can be moved up and down.

On account of the wide opening necessary to permit the brush to perform its functions properly there is a tendency for a carpet to be sucked up slightly into the slot. To prevent this we have spring wire bars 50 extending across the slot in the plane thereof. Each of these wires is provided with a hook-shaped end 51 permanently hooking into an opening in the casing at one edge of the

slot. This connects the wire with the casing at that edge and the wire can be swung to one side and then brought over into a transverse position where its end springs into a notch 52 in the other side which holds it from sidewise motion. It is held in the notch by the spring of the wire.

The machine is operated by a handle 54 which is pivoted to the motor casing 11 and is provided with a stationary hook or link 55. On the motor casing is pivoted a latch 56 which is pressed downwardly by a spring 57. This latch is provided with two notches 58 and 59 in the under side and the spring 15 readily forces it down so that either one of them will catch in the bottom of the hook 55. This holds the handle in nearly vertical position when the device is not in use so that the center of gravity will be between the rollers 14 and 15 or in a rearwardly inclined position for operation. We have shown electric wires connected with this handle for connection with the motor and also hook 60 for supporting them.

In the operation of the device it is only necessary to turn on the current by means of a switch 61 when the motor will operate to draw the air through the nozzle up into the casing 10 through the fan and discharge it into the bag 13 where the dust will collect. The device usually rests on the three rollers 14 and 15, the bottom of the nozzle not pressing on the surface to which it is applied, but if desired the rollers 15 can be adjusted up about the pivots 28 so as to allow the nozzle to come into direct contact with the surface being cleaned. The adjustment of this part is also necessary occasionally for the purpose of cleaning different kinds of surfaces. In all adjusted positions the rollers 15 are yieldingly forced against the wheels 27 and receive their motion by being pushed over the floor. When it is desired to adjust the brush that is accomplished by means of the screws 25 as has been explained. It will be seen that the adjustment of the rollers 15 does not adjust the brush, but the adjustment of the brush does in this form adjust the rollers 15 slightly in the same direction but for practical purposes the two adjustments are independent. Furthermore even when the brush is adjusted up into inoperative position it will be rotated unless the rollers 15 are also adjusted up out of contact with the floor.

In Fig. 12 we have shown a construction slightly different in which the brush is adjusted by the screws 25 as in the other form, but the frame 29 is integral or at least rigidly connected with the two bearing plates 24. In this case, therefore, the adjustment by means of the pin 32 and holes 33 moves the wheels and the brush also by flexing the posts 22, but the brush is not adjusted to the

same extent as the wheels by this motion. 65 The brush can be adjusted in the same way as before but in that case the brush and rollers 15 have a pivotal motion about the stud 32.

Although we have illustrated and described only two embodiments of the invention we are aware of the fact that many modifications can be made therein and certain parts of the invention can be used on other types of cleaners without departing 75 from the scope of the invention as expressed in the claims. Therefore we do not wish to be limited to all the details of construction herein shown and described, but what we do claim is:—

1. In a cleaner, the combination with a casing having a slot in one wall thereof for the entrance of air and dust, of a brush located in the casing parallel with the slot and adapted to engage a surface over which 85 the slot passes, said casing having a projection at the end thereof provided with an extension of said slot connected therewith, and operating means for the brush located outside the casing in the plane of said projection parallel with the end of the casing. 80

2. In a carpet cleaner, the combination of a casing having a slot in the bottom thereof, a brush located in the casing over the slot, said casing having a projection at its end 95 provided with an extension of the slot extending to the end of the projection and communicating with the slot, and operating means for the brush supported above said projection and just beyond the end of said 100 casing.

3. In a carpet cleaner, the combination of a casing having a slot in the bottom thereof and having a projection at its end located outside the casing, a brush located in the 105 casing, operating means for the brush supported over the top of said projection and just beyond the end of said casing, and a cap detachably secured to said casing and covering said operating means and said projection. 110

4. In a carpet cleaner, the combination of a casing, a brush therein, a pair of studs projecting through the ends of the casing from the outside for operating the brush, a 115 wheel on the end of each stud outside the casing, a bearing plate supporting each stud, means for adjusting said bearing plates up and down, and a pair of operating rollers in position to rotate said wheels in their adjusted positions. 120

5. In a carpet cleaner, the combination of a casing having a slot in the bottom thereof, a brush located in the casing and adapted to project into the slot, said casing having a 125 projection at each end provided with a passage extending to the end of the projection and communicating with the slot, a post sup-

ported by the top of each projection, a bearing plate secured to the post and having bearings, shafts supported in said bearings and connected with said brush, a frame pivoted to said bearing plates, and brush operating rollers carried by said frame and connected with said shafts.

6. In a carpet sweeper, the combination with a casing having a slot in the bottom 10 thereof, of a brush located in said casing, a post supported by said casing beyond each end thereof, a bearing plate vertically adjustable on each post and having bearings for supporting the brush, a frame pivoted 15 to said bearing plates, means for adjusting said frame about its pivots, brush operating rollers carried by said frame, and means for operating the brush from the rollers, whereby said brush can be adjusted up and down 20 and said rollers can be adjusted up and down independently of the brush.

7. In a carpet sweeper, the combination with a casing, of a brush therein, a wheel at the end of the brush for turning it, a roller 25 for rolling over the surface to be cleaned engaging said wheel for operating it; means for adjusting said wheel and brush vertically, means for independently adjusting the roller vertically, and means for constantly pressing the roller against the wheel.

8. In a carpet sweeper, the combination with a casing, of a brush therein, a pair of studs projecting through the ends of said casing for operating the brush, a wheel on 35 the end of each stud outside the casing, a bearing plate for supporting each stud, means for adjusting said bearing plates up and down, a frame connected with said bearing plates, a pair of operating rollers 40 carried by said frame, and means whereby said frame can be adjusted up and down.

9. In a carpet sweeper, the combination with a casing, of a brush therein, a pair of studs projecting through the ends of said casing for operating the brush, a wheel on 45 the end of each stud outside the casing, a U-shaped bearing plate for supporting each stud and receiving the wheel, means for adjusting said bearing plates up and down, a frame pivotally connected with said bearing plates, a pair of operating rollers carried by said frame, springs for forcing said operating rollers toward said wheels, said frame having a stud thereon at the center 50 and being formed of spring material, and a bracket supported in stationary position and having holes at different elevations for receiving the last named stud whereby said

frame can be adjusted up and down about its pivots.

10. In a carpet sweeper, the combination with a pair of short shafts in alinement, said shafts having non-circular ends, a brush in the casing having a shaft provided with slots in its ends shaped to receive the ends 6 of said short shafts, one of said slots being centrally located in the end of the brush shaft and the other extending radially to its surface, whereby said brush can be removed and replaced readily, and means on the latter end of the brush shaft for guiding the same into position with respect to the operating shaft and holding it centrally.

11. In a carpet sweeper, the combination with a casing having a pair of short shafts 7 extending therethrough from opposite ends, said shafts having non-circular ends inside the casing, a brush in the casing having a shaft provided with slots in its ends shaped to receive the ends of said short shafts, one of said slots being centrally located in the end of the brush shaft and the other extending radially to its surface, a bracket fixed to the latter end of the brush shaft and having a pair of yielding arms extending past 8 the end thereof near the center, said yielding arms having opposite depressions therein constituting a central circular socket for the brush shaft.

12. In a carpet cleaner, the combination 9 of a casing having slots in its ends, a pair of brush shafts supported outside the casing beyond its ends and projecting into the casing through the slots, air excluding washers movable with the shafts and located on the 9 outside of the casing to exclude air, springs for holding the washers against the casing and a brush in the casing detachably connected with said shafts.

13. In a carpet cleaner, the combination 10 of a casing having slots in its ends, a pair of brush shafts supported outside the casing beyond its ends and projecting into the casing through the slots, and a brush in the casing detachably connected with said 11 shafts, said casing having projections beyond its ends provided with air passages the edges of which engage with the surface to be cleaned, and means for operating said brush carried by said projections and located entirely outside the casing.

In testimony whereof we have hereunto set our hands.

FRANK J. QUIST.
ANDERS E. ANDERSON.
